UNITED STATES PATENT OFFICE.

WILLIAM ROTHMAN, OF RACINE, WISCONSIN.

GROOVING-TOOL.

1,158,725.

Specification of Letters Patent.

Patented Nov. 2, 1915.

Application filed September 25, 1914. Serial No. 863,506.

To all whom it may concern:

Be it known that I, WILLIAM ROTHMAN, a subject of the Emperor of Austria-Hungary, and a resident of Racine, county of Racine, and State of Wisconsin, have invented certain new and useful Improvements in Grooving-Tools, of which the following is a specification.

The main objects of this invention are 10 to provide an improved form of grooving tool particularly adapted for use in locking the seams of sheet metal pipes and tubes; to provide improved means for adjusting the jaws of the tool to fit various 15 sized seams whereby the tool is capable of replacing several such tools, each of a different size, heretofore used for locking pipe seams; to provide improved means for maintaining the parallel alinement of the 20 jaws; and to provide a tool of this kind which is simple and inexpensive to manufacture.

An illustrative embodiment of this invention is shown in the accompanying drawings in which—

Figure 1 is a perspective view of the improved grooving tool. Fig. 2 is a side elevation of the same. Fig. 3 is a right end elevation of the tool. Fig. 4 is a view illustrating the manner in which the tool is used.

In the construction shown in the drawings, the tool comprises a head or body member 5 integrally formed on a shank or handle 6. The tool is preferably made of 35 forged steel.

A jaw 7 is integrally formed along one edge of the body member 5, with which a movable jaw 8 is arranged to coact. The movable jaw 8 is shiftably mounted between guides 9 and 10 integrally formed at the ends of the body member 5 and extending transversely to the fixed jaw 7. A bolt 11, carried by the fixed jaw 7, supports the movable jaw 8, the shifting of which, 40 toward and away from the movable jaw, is controlled by means of a nut 12. A spring 13 interposed between the jaws 7 and 8 embracing the rod 11, normally urges the jaw 8 away from the jaw 7. A shoulder or 45 ledge 14 is integrally formed on the body member 5 inwardly of, and extending along, the guide 10. A recess 15 is formed in the corresponding corner of the movable jaw 8 so as to snugly fit the shoulder 14 and coact 50 therewith for obtaining a truer parallel alinement of the jaws 7 and 8. A scale 16

is laid off on the guide 9 so as to register with the advancing edge 17 of the movable jaw 8 for the purpose of indicating the distance between said jaws, and to facilitate 60 the setting of the jaws to fit a certain sized seam.

The device herein shown is used in the following manner:—The jaws 7 and 8 are first adjusted so as to fit the seam 18 formed 65 by the interlocking edges of the pipe or tube 19. The operator then grasps the tool by the handle 6 and sets the jaws over the seam, as shown in Fig. 4, and strikes a blow on the end of the handle 6. The metal is 70 forced down, as shown in Fig. 4, so as to lock the seam and prevent it from becoming disengaged before it is clenched or sealed, as the case may be. By virtue of the adjustability of the jaws 7 and 8, this tool is 75 capable of replacing the several different sized tools that heretofore have made up a complete equipment of grooving tools. It is simple and inexpensive to manufacture and saves a tinner considerable expense in 80 equipping himself for this kind of work.

Although but one specific embodiment of this invention has been herein shown and described, it will be understood that some details of the construction shown may be 85 altered or omitted without departing from the spirit of this invention as defined by the following claims.

I claim:—

1. A tool for locking the seams of sheet 90 metal tubes, comprising a handle shank, a head carried by said shank, a pair of jaws supported on said head in substantially parallel relation and adapted to engage the opposite edges of the seam to be locked, said 95 jaws being movable toward and away from each other for varying the distance between them whereby said tool is capable of being used for seams of various sizes.

2. A tool for locking the seams of sheet 100 metal tubes, comprising a handle shank, a head carried by said shank, a pair of jaws supported on said head in substantially parallel relation and adapted to engage the opposite edges of the seam to be locked, one 105 of said jaws being rigid on said head and the other being movable toward and away from said one jaw for varying the distance between said jaws whereby said tool is capable of being used on seams of various sizes. 110

3. A tool for locking the seams of sheet metal tubes, comprising a handle shank, a

head carried by said shank, a pair of jaws supported on said head in substantially parallel relation and adapted to engage the opposite edges of the seam to be locked, one of said jaws being rigid on said head, and guide members formed on said head transversely to said one jaw, said other jaw being shiftably mounted between said guide members so as to vary the distance between said jaws whereby said tool is capable of being used on seams of various sizes.

4. A tool for locking the seams of sheet metal tubes, comprising a handle shank, a head carried by said shank, a jaw integrally formed along one side of said head, guide members on said head extending transversely to said jaw, a movable jaw shiftably mounted on said head between said guide members and disposed parallel to said one jaw, a bolt carried by said fixed jaw and extending through said movable jaw, a spring interposed between said jaws normally urging said movable jaw away from said fixed jaw, and a nut on said bolt adapt-

ed to be actuated for shifting said movable jaw for varying the distance between said jaws whereby said tool is capable of being used on seams of various sizes.

5. A tool of the class described, comprising a body member, a jaw rigidly fixed thereon, guides on said member extending transversely of said fixed jaw, a movable jaw shiftably mounted on said member between said guides and disposed parallel to said fixed jaw, a shoulder formed on said body member at the side of one of said guide members, said movable jaw being recessed to fit said shoulder and adapted to coact therewith for maintaining the parallel relation of said jaw, and means for shifting said movable jaw toward and away from said fixed jaw for the purpose specified.

Signed at Chicago this 23rd day of Sept. 1914.

WILLIAM ROTHMAN.
